UNITED STATES PATENT OFFICE.

LOUIS A. MORAN, OF GROSSE POINTE FARMS, MICHIGAN.

GARBAGE-RECEPTACLE.

1,028,898.

Specification of Letters Patent. Patented June 11, 1912.

Application filed July 13, 1911. Serial No. 638,253.

To all whom it may concern:

Be it known that I, LOUIS A. MORAN, a citizen of the United States, residing at Grosse Pointe Farms, in the county of 5 Wayne, State of Michigan, have invented certain new and useful Improvements in Garbage-Receptacles; and I do declare the following to be a full, clear, and exact description of the invention, such as will enable others skilled in the art to which it 10 pertains to make and use the same, reference being had to the accompanying drawings, and to the characters of reference marked thereon, which form a part of this 15 specification.

This invention relates to a garbage receptacle and consists in the construction and arrangement of parts hereinafter more fully set forth and pointed out particularly in the 20 claims.

The object of the invention is to provide a garbage receptacle which may be placed in the ground and kept closed so as to exclude flies therefrom, provision being made 25 for readily opening the receptacle when it is desired to place garbage therein, and for permitting the vessel containing the garbage to be readily removed from the receptacle by the collector.

The above object is attained by the structure illustrated in the accompanying drawings, in which:—

Figure 1 is a general view in perspective of a garbage receptacle constructed in accordance with my invention. Fig. 2 is a view showing the receptacle in section and the upper portion in elevation. Fig. 3 is a fragmentary view partly in section showing the position of parts when opened for 40 the reception of garbage. Fig. 4 is a plan view of Fig. 1.

Referring to the characters of reference, 1 designates a section of sewer crock placed vertically in the ground with its upper end 45 projecting some distance above the surface. The lower end of the crock is closed to form a bottom by a filling 2 of concrete, or other suitable material. The top 3 of the receptacle is circular to conform to the shape of 50 the crock and is supported upon the upper edge thereof. The under side of the top 3 is provided with concentric flanges 4 and 5, respectively, adapted to embrace the top of the crock to retain the cover in place. 55 Formed centrally through the top or cover 3 is a square opening surrounded by a fixed

hood 6. Mounted within the hood to extend therethrough into the receptacle are the spouts 7 and 8, respectively. The spout 7 is pivoted through the sides thereof to the 60 hood 6, as shown at 9, and the spout 8 is in like manner pivoted to the hood, as shown at 10. The parts are so formed as to allow the sides 11 of the spout 8 to lie within the sides 12 of the spout 7. When the spouts are 65 closed, as shown in Figs. 1 and 2, their upper edges fit closely together and the overlapping sides thereof assist in forming a tight closure for the mouth of the hood which is tapering in form to shed the water 70 therefrom.

To provide for operating the pivotally mounted spouts to swing them upon their pivots to the open position shown in Fig. 3, links 13 and 14 are employed whose outer 75 ends are pivoted to the sides of the spouts, respectively and whose inner ends are pivotally joined at 15 to a short link 16 which is in turn pivoted to the inner end of a lever 17 fulcrumed at 18 to the top or cover 3. 80 Mounted under the outer end of said lever is a compressible spring 19 whose tension is normally exerted to hold the pivoted spouts in the closed position, as shown in Fig. 2. 85 When it is desired to open the spouts, pressure is applied by the foot to the outer end of the lever 17, thereby raising the inner end of said lever to actuate the links 13 and 14, which form the elements of a toggle lever, to swing the spouts 7 and 8 outwardly 90 on their pivots to the position shown in Fig. 3. This operation causes the lower ends of said spouts to swing together and form a chute which will direct the garbage, or other refuse, centrally into the pail or container 20 seated in the crock upon the bottom 2. Upon releasing the pressure upon the outer end of the lever 17, the expansive force of the spring 19 will return the spouts to the closed position shown in Figs. 1 and 100 2, a position in which the mouth of the hood is tightly closed by the pivoted spouts, which in this respect form complementary portions of the cover of the receptacle.

When the pail or container has become 105 filled, or when the collector of refuse desires to remove the pail or container, access to said pail may be readily had by lifting the cover from the top of the crock through the medium of the handles 21 which are attached to the upper edges of the spouts. 110 By removing the whole top in this manner,

ready access to the pail or container is afforded, enabling it to be taken out and emptied, and readily replaced in the receptacle, after which the cover and its pivoted spouts 5 are replaced thereon, said spouts at once becoming operative to close the receptacle and to serve as a means for directing refuse into the pail within the receptacle when the lever 17 is actuated to swing the pivoted spouts 10 to the open position.

Having thus fully set forth my invention, what I claim as new and desire to secure by Letters Patent, is:—

1. A receptacle having a cover, spouts 15 pivotally mounted in the cover to swing together at their upper ends and close the opening into the receptacle, said spouts being movable upon their pivots to expose the opening through the cover and form a chute 20 below said opening to direct refuse into the receptacle, and a removable container within said receptacle below said spouts.

2. A receptacle having a cover, spouts pivotally mounted in the cover to swing together at their upper ends and close the 25

opening into the receptacle, said spouts being movable upon their pivots to expose the opening through the cover and form a chute below said opening to direct refuse into the receptacle, and means for actuating said 30 spouts in unison.

3. A receptacle having a cover, spouts pivotally mounted in the cover to swing together at their upper ends and close the opening into the receptacle, said spouts being movable upon their pivots to expose the opening through the cover and form a chute below said opening to direct refuse into the receptacle, a removable container within the receptacle below said spouts, pivoted links 35 connected to the sides of the spouts, and an operating lever pivotally connected to said links.

In testimony whereof, I sign this specification in the presence of two witnesses.

LOUIS A. MORAN.
